UNITED STATES PATENT OFFICE.

ARNOLD J. HESKETT, OF REX, OREGON.

BLOCK-MAKING MACHINE.

Application filed March 19, 1925. Serial No. 16,600.

This invention relates to machines for making concrete blocks or bricks or other similar articles. For convenience in illustrating I have herein described a machine for making hollow blocks, but it is to be understood that my invention may be applied also to machines for manufacturing solid blocks, bricks or other similar articles.

One of the objects of my invention is to supply simple and dependable operating mechanism for the machine so as to reduce the hazard of breakage and the tendency of the coacting parts to become disarranged. Another object of the invention is to make the machine as fully automatic as is practical. Another object is to provide for more effectively tamping the blocks and otherwise preparing them during the process of manufacture. Other objects of the invention will be apparent from a consideration of the accompanying drawings, and the following description thereof:

Of the drawings, Fig. 1 is a front elevation of a block forming machine which embodies features of my invention; Fig. 2 is a side elevation of the machine; Fig. 3 is a plan view of the molds and the operating mechanism; Fig. 4 is a plan view of a hopper for feeding concrete to the molds; and the operating mechanism thereof; Fig. 5 is a bottom view of one of the tampers; Fig. 6 is a plan view of a compound machine without the tampers in which four machines are operated by one driving mechanism; and Fig. 7 is a bottom view of an operating cam and a spider therefor.

The machine comprises the frame 10 upon which are mounted molds 11, a movable hopper 12 for supplying the molds with concrete, and a chute 13 through which the concrete passes from the supply bin 14 to the portable hopper 12. The machine also comprises tampers 15 and operating mechanism 16 therefor, the tamping mechanism being supported in any suitable manner for example by means of beams supported from the ceiling of the building. Mounted upon the frame 10 are cams 17 and 18 for operating the machine, and a motor 19 is provided for operating the cams and also the tampers.

The machine in this instance comprises two molds for forming hollow blocks each mold having a side board 22, and a central board 23 forms a partition between the two molds. The rear sides of the molds are formed by a board or plate 24 and the front

sides by a board or plate 25. The bottoms of the molds are formed by a pallet 26 upon which the blocks are molded, and by means of which they may be lifted and removed from the machine. Within the molds are cores 27 and 28 which form the hollows in the blocks.

In making blocks by what is called the semi-wet process the concrete is tamped in the mold and before the concrete sets the blocks are removed. As a consequence the blocks must be handled carefully and the sides and cores of the mold must be removed by lateral movement. Instead of moving the side-boards away from the blocks or the blocks away from the boards of the mold, the boards are slid laterally until free from the concrete. To provide for this I mount the boards 22 and 23 slidably on the frame 10 and fix the boards rigidly together by means of a plate 30, or by some other suitable means. I then provide mechanism for sliding the boards backwardly and forwardly in order to remove them from the blocks and for returning them to their normal positions for forming the molds.

In order to operate these boards, I mount upon a shaft 31 a cam plate 18, the plate having a cam-way 33, and in this cam-way is positioned, a roller 34 which is rotatably fixed to a beam 35. The beam is fixed to the plate 30 and has a guide fork 36 which straddles the shaft 31. Obviously as the cam 18 rotates the roller 34 will be moved forwardly or backwardly, as the case may be, carrying with it the boards 22 and 23.

The cores 27 and 28 are mounted in the frame 10 for vertical movement. When the blocks have been tamped and are ready to be removed these cores are allowed to move downwardly by virtue of their weight until the upper ends thereof are entirely out of the way. To accomplish this the cores are fixed to a core plate 40 which is supported by a slidably mounted vertical rod 41, and means are provided for sliding the rod 41 upwardly and downwardly when desired. Any suitable means may be provided for this purpose, but I prefer to operate the rod 41 by means of the cam 18. In practice the movement of the cores of the mold may be synchronous with the movement of the side boards of the molds. I, therefore, provide a lever 42, the upper end of which normally rests against a block 43, fixed to one of the boards 22. As the block 43 moves back-

wardly with the board the lower end of the lever 42 can move forwardly and allow the forward end of a lever 44 to move downwardly. This lever end is forked and is pivoted to the rod 41 by means of links 45, and hence, as the arm of the lever 44 is allowed to move downwardly, the rod 41, with the core plate and cores, will sink to the desired point. If for any reason the weight 20 of the cores and the other mechanism is not sufficient to force them downwardly a block 46 fixed to the side board, may be provided for acting on the upper end of the lever 42, and thus forcing the cores downwardly. 25 When the core plate sinks the pallet is supported by the frame 10.

The front side 25 of the molds is preferably fixed to the core plate 40 and hence is lowered and raised as the cores are lowered 20 and raised. However, this front side may be independently removable, as is the case with many ordinary machines. In order that the blocks may be carefully removed from the machine a pallet 26 is provided to 25 form the bottom of the molds. In this pallet are openings 50 through which the cores 27 and 28 pass. When the pallets with the blocks thereon are racked in the steam curing room, these openings allow the steam to circulate through the hollows in the blocks and between the blocks. 30

In operation, when a pallet of blocks has been removed an empty pallet is placed on the framework against the rear mold side 24 35 and with the openings 50 registering vertically with the upper ends of the cores. The mold boards 22 and 23 are then forced forwardly over the upper surface of the pallet and, simultaneously, the cores are forced upwardly into the openings 50 of the pallet, and, at the same time, the front board 25 is elevated to its normal position. When the blocks have been completed this process is reversed, and the operator manually elevates the pallet with the two blocks thereon, giving them a sliding motion on the rear board 24, and removes them from the machine and inserts another pallet. 45

I provide also automatic means for passing 50 concrete into the molds. This comprises the slidably mounted hopper 12. This hopper, by means of the bearings 60, is slidably mounted on the rod 61, the rod being fixed to the framework. Mounted on a beam 62, 55 fixed to the rear side of the hopper, is a cam roller 63 which plays in a camway 64 of the cam disk 17. This disk is also fixed to the vertical shaft 31, and hence rotates synchronously with the cam, 18. The shaft 60 is rotated in any suitable manner, such as by means of a worm wheel 66 operated by a worm 67 mounted on the shaft 68 of the motor 19, the motor having suitable reduction gearing 69 for obtaining a suitable speed 65 of the shaft 31.

In operation, when the molds are being formed, as hereinabove described, the hopper 12 is positioned immediately under the chute 13, and a plate 70, fixed to the framework, forms the bottom of the hopper 12. The 70 hopper receives the concrete through the chute ready to be delivered to the molds. When the molds are formed, the cam 17 moves the hopper forwardly until it comes at rest over the molds and the concrete passes from the hopper into the molds, enough concrete being delivered to fill the molds with a material amount of surplus. The tamping mechanism is then set in operation and the tampers 15 tamp the concrete suitably for 80 the purpose. The tampers are then stopped, the hopper 12 is moved backwardly and the finished blocks are removed from the machine as hereinabove described. 85

The tamping mechanism may be any ordinary form of tamping mechanism and may be operated in any suitable manner, such as by means of the belt 75 and the wheel 76 which operate the shaft 77. This shaft carries arms 78 each of which operates an arm 79 fixed to the respective tamper shafts 80, thus elevating the tampers and allowing them to fall of their own weight. When the tamping is to be stopped, blades 81 are moved forwardly so as to pass under collars 82 and thus hold the tampers so as to prevent their moving downwardly when released. 90

In operation, as the hopper 12 reaches its forward normal position, an arm 85, fixed to the hopper, strikes an arm 86, fixed to a rotatably mounted shaft 87. This shaft carries the blades 81, and thus the blades are moved out from under the collars 82 and the tampers are allowed to operate, it being understood that the wheel 76 is rotated continuously. When the cam 17 begins to move the hopper 12 rearwardly, the arm 86 is released and a spring 88 rotates the shaft 87 so as to throw the blades 81 forwardly to receive the collars 82 and stop the tamping. 100

It will thus be seen that I have provided an automatic machine for forming these hollow blocks. The motor may be stopped, or started, in any suitable manner, such as by means of an electric switch 90, so that operations may be stopped at any time when desired. A magnetic brake 89 set in operation by opening the switch 90, brings the mechanism quickly to rest. For instance if it is desired to process the front or sides of the blocks, the mechanism may be stopped when the blades and front board have been removed and the blocks finished as desired. If desired for such purpose the front board may be manually and independently removable, so that the processing of the front sides of the blocks can be carried through before the molds or side boards are removed. In order to trowel the upper surface of the 110 115 120 125 130

blocks I provide a trowel strap 91 fixed to the hopper so that it is carried over the upper surface of the blocks as the hopper is removed. This strap is mounted on the hopper, so that it may be adjusted vertically.

Although the cores may be of any shape or length desired, I have provided herein cores 27 which extend upwardly to within about an inch of the upper surface of the mold sides, so that the hollows formed by these cores do not extend clear through the blocks. I provide, however, the central cores 28 long enough to reach to the upper edges of the mold sides, so that they form hollows clear through the blocks, the trowel 91 scraping the concrete off from the upper ends of the cores 28, as it moves rearwardly. Also in order to more perfectly tamp the concrete I provide a flange 95 extending around the edge of each tamper. This flange tamps the concrete between the cores and the mold walls. I also provide projections 96 which extend downwardly and tamp the concrete over the ends of the shorter cores 27. By these means the outer edge of the blocks and the thin portions over the ends of the short cores 27 are very thoroughly tamped and hence are strengthened.

Fig. 6 illustrates a compound machine in which four units are operated by a single driving system. One object of this machine is to provide a unit machine to which other units may be added if desired, without any material modifications of the elements of any of the units and without adding additional driving means. In this case I show four units 100, 101, 102 and 103, each of which, so far as the tampers, hoppers and molds are concerned, is substantially the same as the single machine already described; and any one of these units, including the central cam operating mechanism and driving means, is substantially the same as the single machine. A block molding manufacturer for instance may install the unit 100, together with the cam mechanism 104 and the driving means 105, and carry on block manufacturing work efficiently and in all respects as if a single machine only were used. He may, however, whenever desirable, attach another unit 102, using the same cam and driving elements without change. Even the motor 105 need not be replaced by a higher power motor, for the reason that the moving elements of the two unit are not synchronous, and while power is being used for some of the elements of one unit it is not used for those of the other. For instance the two sets of tampers would not be operated simultaneously, nor would the heavier work of any of the moving parts of the two units be simultaneous.

In combining the second unit 102 it is necessary only to install the second unit on the side of the cam shaft 98 opposite the

first unit, insert the cam rollers of the hopper and the mold sides in the proper cam-ways, and provide suitable mechanism for operating the tampers. Similarly units 101 and 103 may be installed if desired. As each of these units are substantially the same as the machine already described it is not deemed necessary to enter into the details. The additional elements for driving the tampers may be all old and well known such as are plainly indicated in the drawing. In installing the new additional units, it is necessary only to insert a bevel gear 106, on the driving shaft 107, of the original unit and associate with this gear the gears 108 and 109, when desired. The gear 108 operates the shaft 110 which operates, by means of a belt 111, the tamper mechanism of the unit 101. Gear 109 operates the tampers of the unit 103, and bevel gears 112 operate the shaft 13 of the unit 102.

Inasmuch as the beams 36 and 62 of the original machine, would be in the way of similar beams of additional units, a spider 114, having slots 115 therein, and being rigidly fixed to the frame, may be inserted when the additional units are added, the roller 116 of the units playing in these slots. In this manner forked ends for the beams 117 are not needed. But, if desired, forked beams similar to 36 and 62 may be used, as the forks can be offset, when additional units are added, so as not to conflict with each other.

It will be seen that by use of this machine I provide means for manufacturing blocks with four units, which may be very compactly arranged with reference to each other, and may be operated at a minimum of expense for power, and which involve much less complication and expense than if four entire machines were used. It will be readily seen that the four hoppers 120, 121, 122 and 123 may all be fed by the single central concrete bin 14 provided for the single machine. Hence, not only is the mechanical expense materially reduced and the work expedited, but one workman preparing the plastic material for the molds can prepare for all of the machine simultaneously, and a single operator might operate the four machine units by successfully substituting the independent pallets for the full pallets at the proper time. Switches 124 may be provided for each unit so that the operator may stop the machine when working with any one of the units.

Although I have described with much detail various elements of the single machine and the compound machine, yet it will be understood that various modifications herein could be made by those skilled in the art without departing from the spirit of my invention as disclosed by the following claims. Furthermore it will be understood that any

form of brick or block making material could be used with the machines and either of these machines could be used for making blocks or bricks either with processed surfaces or not. Furthermore the combined machine could be used for making simultaneously bricks and blocks, as one or more of the units could be used for one purpose and others for other purposes if desired.

10 I claim as my invention:

1. A block making machine comprising a frame, a tamper, a hopper slidably mounted on said frame, means for passing plastic material into said hopper, block molds mounted on said machine, means for moving said hopper, and means adapted to be set in motion by said hopper for operating said tamper.

2. In a block molding machine, a mold comprising slidably mounted sides and a slidably mounted front plate, means for operating said sides, and means set in motion by said side operating means for operating said front plate.

3. In a block molding machine, a mold comprising sides mounted for horizontal movement, and cores mounted for movement, means for moving said sides horizontally, and means set in operation by said side mechanism for moving said cores.

4. In a block molding machine a mold, comprising sides, a front plate, and cores, means for moving said sides horizontally, and means for moving said plate and cores vertically.

5. In a block making machine a mold comprising sides, a core plate, a core fixed to said plate, and a front mold plate fixed to said core plate, means for reciprocating said core plate vertically, and means for reciprocating said sides horizontally.

6. In a block making machine a core plate, a core fixed to said plate, a front mold plate fixed to said core plate, mold sides, means for reciprocating vertically said core plate, means for reciprocating horizontally said sides, and a pallet adapted to be placed over said core plate to form the bottom of the block mold.

7. In a block making machine a core plate, a core fixed to said plate, a front mold plate fixed to said core plate, mold sides, means for reciprocating vertically said mold plates, means for reciprocating horizontally said mold sides, a pallet adapted to be placed on said core plate to form the bottom of the block mold, said pallet having an opening therein through which said core may project.

8. In a block forming machine a mold, cores projecting upwardly from the bottom of said mold, sides for said mold, the upper end of one of said cores being substantially flush with the top of said sides, the upper end of another of said molds being mate-

rially lower than the upper edges of the sides, means for passing block forming material into said mold, and means for tamping said material; said tamping means comprising a tamper arranged to reciprocate vertically, the lower surface of said tamper having a projection thereon over the lower of said cores.

9. In a block forming machine a mold, cores projecting upwardly from the bottom of said mold, sides for said mold, the upper end of one of said cores being substantially flush with the top of said sides, the upper end of another of said molds being materially lower than the upper edges of the sides, means for passing block forming material into said mold, and means for tamping said material; said tamping means comprising a tamper arranged to reciprocate vertically, the lower surface of said tamper having a projection thereon over the lower of said cores, and having a flange projecting downwardly around the outer edge of said surface.

10. In a block forming machine a vertical shaft, means for rotating said shaft, a cam fixed to said shaft, a slidably mounted hopper, and operating means connecting said hopper with said cam.

11. A block forming machine comprising a frame, a shaft rotatably mounted in said frame, a cam fixed to said shaft, a hopper slidably mounted on said frame, operating means connecting said cam with said hopper, a second cam fixed to said shaft, mold forming elements slidably mounted in said frame, operating means connecting said elements with said second cam, and means for operating said shaft.

12. In a block making machine slidably mounted elements adapted to form the front and sides of a mold, a movable support for the bottom of said mold, and common means for simultaneously moving said front, and support relative to said sides.

13. In a block making machine slidably mounted elements adapted to form the front and sides of a mold, a movable support for the bottom of said mold, common means for simultaneously moving said front and support relative to said sides, means for moving said sides horizontally, and a movable bottom for said mold normally resting on said support.

14. In a block making machine slidably mounted elements adapted to form the front and sides of a mold, a movable support for the bottom of said mold, means for moving said sides horizontally, and for simultaneously moving said front and support vertically, a movable bottom for said mold normally resting on said support, and means for supporting said bottom when said movable support is removed.

15. In a block making machine, a mold, a

- slidably mounted hopper for feeding block forming material into said mold, means for moving said hopper into its operative position, a tamper for said mold, means for operating said tamper, and means actuated by said hopper means for setting in operation said tamper operating means.
16. In a block making machine a mold, a slidably mounted hopper for feeding block forming material into said mold, means for moving said hopper into its operative position, a tamper for said mold, means for operating said tamper, and means actuated by said hopper means for setting in operation said tamper operating means and for preventing operation of said tamper operating means.
17. In a block forming machine a tamper, a slidable hopper, movable mold elements, power means, means operatively connecting said power means with said tamper, means operatively connecting said power means with said hopper, and means operatively connecting said power means with said mold elements, and means actuated by said hopper operating means for disconnecting said tamper operating means when said hopper is moving from its operating position.
18. A block making machine comprising a tamper, a movable hopper, and a mold having a vertically movable element and a horizontally movable element, common means for operating said tamper, said hopper, and said movable element.
19. In a block molding machine a frame, mold sides mounted for horizontal movement in said frame, a mold front mounted for vertical movement in said frame, a mold bottom support mounted for vertical movement in said frame, and common means for simultaneously moving all of said mold elements.
20. In a hollow block forming machine, a mold comprising sides mounted for horizontal movement, a core mounted for vertical movement, means for moving said sides horizontally, means operated by said sides for moving said core upwardly, said core being adapted to move downwardly when released by said sides, and means actuated by said sides for forcing said mold downwardly.
21. A block forming machine comprising a plurality of independent molds, a movable hopper for each of said molds, and a single cam for operating said hoppers.
22. A block forming machine comprising a plurality of independent molds, a movable hopper for each of said molds, a single cam for operating said hoppers, said cam being adapted to move one of said hoppers in one direction as another hopper is being moved in another direction.
23. In a block molding machine a plurality of molds, a movable hopper for each of said molds, and means for reciprocating said hoppers, said reciprocations being non-synchronous.
24. A block molding machine comprising a plurality of independent molds, each of said molds having movable elements, common means for reciprocating said elements, said reciprocations being discontinuous and non-synchronous.

In testimony whereof, I hereunto set my hand.

ARNOLD J. HESKETT.
